Inventor:
 Matthias Gabriel.

United States Patent Office.

MATTHIAS GABRIEL, OF NEWARK, NEW JERSEY.

Letters Patent No. 67,527, dated August 6, 1867.

IMPROVEMENT IN ROTARY STEAM ENGINES.

The Schedule referred to in these Letters Patent and making part of the same.

TO ALL WHOM IT MAY CONCERN:

Be it known that I, MATTHIAS GABRIEL, of Newark, in the county of Essex, and State of New Jersey, have invented certain new and useful Improvements in Rotary Engines; and I do hereby declare that the following is a full, clear, and exact description of the same, reference being had to the accompanying drawings, making a portion of this specification, in which—

Figure 1 is a vertical transverse section of a rotary engine constructed according to my invention.

Figure 2 is a side view of the same.

Similar letters of reference indicate corresponding parts in both figures.

This invention consists in the arrangement of two steam pipes or passages at opposite sides of the cylinder of a rotary engine, and in such relation with the rotating piston and the valve-chest of the same as to insure a very efficient action of the steam upon the said piston. The invention further consists in a novel means, whereby the valve may be properly operated with reference to the movement of the rotary piston. The invention further consists in two sliding abutments operated by a cam on the piston-shaft, and so arranged in relation with the hereinbefore-mentioned steam pipes or passages that the pressure of the steam upon the piston is rendered nearly continuous.

To enable others to understand the nature and construction of my invention, I will proceed to describe it with reference to the drawings.

The cylinder of the engine is shown at A, and is supported by a suitable base, a. This cylinder is furnished at its top or upper side with a valve-chest, b, in which is placed the slide-valve B, and which is furnished with an induction pipe, c. The eduction pipe or passage is shown at d, and of course communicates with the eduction-chamber A* of the valve B. C and C* represent two steam pipes or passages, situated one at each side of the cylinder, with their upper ends communicating with the valve-chest b, and their lower ends placed nearly opposite each other and communicating with the interior of the cylinder A, as shown at b*, in fig. 1. The central transverse shaft e has secured upon it the rotating piston D, which is of cylindrical form, and is furnished at one side with a radially projecting abutment, f, the edges of which, being provided with packing of any suitable variety, are kept in close contact with the inner surface of the cylinder A as the said abutment is carried around by the rotation of the piston. E and E* indicate two sliding abutments which are situated in a horizontal position at opposite sides of the cylinder A, one of the said sliding abutments being placed below the front b* of one of the steam pipes C C*, and the other being located above the corresponding opening a* of the other steam pipe. These sliding abutments E E* work in suitable guides formed at the sides of the cylinder, as indicated at g, and are furnished with rods or stems, h, which, passing out through stuffing-boxes i, have their outer extremities firmly attached by curved straps B* to the ends of a vibrating-bar, F, which is situated at one end of the cylinder A. The central part of this bar F is curved, as shown in fig. 2, so that its movements may not be interfered with by the outwardly extending portion of the shaft e, and has attached to it at a suitable distance apart two friction-rollers k, and secured upon the end just mentioned of the shaft e, between the aforesaid friction-rollers k is a cam, G, the straight portions a' b' of the circumference of which act upon the friction-rollers k, to vibrate the bar F, to operate the sliding abutments E, and the semicircular portion a' of the said circumference serving to hold the bar F, and consequently the aforesaid abutments E E*, in a stationary position at intervals during the operation of the engine, as hereinafter more fully explained. That end of the shaft e opposite to that at which the cam G is secured is furnished with an eccentric, shown in dotted outline at I, and which operates a connecting-rod, m, the upper end of which is pivoted to an arm, n, formed upon a toothed sector, r, which gears into a rack, s, provided upon the outer end of the valve-stem u, which passing through a stuffing-box, v, has its inner end attached to the slide-valve B. The parts being in the position shown in the drawings, the pressure of steam admitted through the steam pipe C into the cylinder A, between the sliding abutment E*, and the abutment f of the piston D, upon the abutment f, last mentioned, turns or partially rotates the piston, until the said abutment f approaches the part b* of the steam pipe or passage C*, whereupon the cam G operates the bar F to move outward the sliding abutment E*, and bring inward the other sliding abutment E, simultaneously with which the eccentric I operates the valve B to permit the steam to pass inward through the pipe or passage C*, into the space in the cylinder between the sliding abutment E and

the abutment *f* of the piston; the pressure of such steam upon the abutment *f* causing the piston to complete the revolution, so that, by thus admitting steam to the cylinder alternately through the pipes or passages C C*, the continued rotation of the piston is secured, the exhaust steam in front of the abutment *f* of the piston passing out through each of the aforesaid pipes C C*, alternately with the inward passage of steam through the same. The sliding abutments E E* are held in the required stationary position while the steam is acting upon the abutment *f* of the piston by the action of the semicircular part *a'* of the circumference of the cam upon the adjacent friction-roller of the vibrating-bar. The said cam acting upon the said rollers only by means of the straight portions of such circumference to vibrate or slide the bar to move the sliding abutments E E* in and out, as hereinbefore explained.

What I claim as my invention, and desire to secure by Letters Patent, is—

The sliding abutments E E*, when connected by the yoke or bar F, and operated simultaneously by the cam G on the axis of the rotating piston D, substantially as and for the purpose set forth.

MATTHIAS GABRIEL.
